[57] CLAIM

The ornamental design for a ceiling unit, as shown and described.

DESCRIPTION

FIG. 1 is a front perspective view of a ceiling unit showing our new design, the rear being plain and unornamented, the pattern being repetitive as in FIG. 1 of the drawing disclosure, and the ceiling unit being of a conventional thickness; and,

FIG. 2 is a front elevational view showing one tile from the ceiling unit in greater detail.

FIG. 2
